UNITED STATES PATENT OFFICE

167,612

RADIO CABINET

Robert D. Budlong, Skokie, Ill., assignor to Zenith
Radio Corporation, a corporation of Illinois

Application February 29, 1952, Serial No. 18,732

Term of patent 7 years

(Cl. D56—4)

To all whom it may concern:

Be it known that I, Robert D. Budlong, a citizen of the United States, residing at Skokie, in the county of Cook, State of Illinois, have invented a new, original, and ornamental Design for a Radio Cabinet, of which the following is a specification, reference being made to the accompanying drawing, forming a part thereof.

The single figure is an end perspective view of a radio cabinet, showing my new design.

The design of the side of the cabinet not shown is similar to the design of the side shown and the design of the end of the cabinet not

shown is similar to the design of the end shown.

I claim:

The ornamental design for a radio cabinet, as shown and described.

ROBERT D. BUDLONG.
